United States Patent Office

Des. 196,198
Patented Sept. 3, 1963

196,198

COMBINED SPRAYER AND STORAGE CONTAINER FOR CHEMICALS OR THE LIKE

Leon M. Corning, Redwood City, Robert L. Friedenthal, San Mateo, and Robert E. Sarafan, San Francisco, Calif., assignors to Advance Chemical Company, San Francisco, Calif.

Filed May 18, 1962, Ser. No. 70,193

Term of patent 14 years

(Cl. D58—5)

FIG. 1.

FIG. 3.

FIG. 2.

FIG. 4.

FIG. 5.

FIG. 1 is a top plan view of a combined sprayer and storage container for chemicals, or the like, showing our new design;

FIG. 2 is a side elevation thereof;

FIG. 3 is an end elevation thereof;

FIG. 4 is an end elevation thereof; and

FIG. 5 is a bottom perspective view thereof.

The dominant features of the design reside in the portions shown in full lines in the drawings.

We claim:

The ornamental design for a combined sprayer and storage container for chemicals, or the like, as shown and described.
